D 17120

UNITED STATES PATENT OFFICE.

JOHN REIFFENSTEIN, OF SYRACUSE, NEW YORK, ASSIGNOR TO THE SYRACUSE STOVE COMPANY, OF SAME PLACE.

DESIGN FOR A STOVE OR RANGE.

SPECIFICATION forming part of Design No. 17,120, dated February 15, 1887.

Application filed December 24, 1886. Serial No. 222,512. Term of patent 7 years.

To all whom it may concern:

Be it known that I, JOHN REIFFENSTEIN, of Syracuse, in the county of Onondaga, in the State of New York, have invented a new Design for Stoves, of which the following, taken in connection with the accompanying engraving, is a full, clear, and exact description.

The accompanying engraving is a perspective view of a cooking stove or range embodying my design in configuration and ornamentation.

K is the base; L, the warming-closet mounted thereon, above which is the range proper, M, and upon the top of the latter is the high shelf N. The horizontal projection k at the base, I embellish on its top surface by rectangular panels o o o o and intervening circular panels, p p p, all arranged in a row on the said surface. Across the central portion of each rectangular panel is a raised line or bar, r, formed into a rectangular loop, and along the sides of this line are arranged a series of small raised circles, s, with depressed center. In the center of each of the circular panels is a rosette, u. The horizontal projection k', which forms the hearth beneath the oven-door and above the warming-closet, is ornamented in same manner as the one already described.

The supporting-brackets of the high shelf are arranged on either side of the smoke-flue, which forms the center, and have a triangular base, R, the interior of which is reticulated. The upper part, T, of the bracket also approximates the triangular in shape, and is composed principally of a band, v, formed into square and rectangular loops for the interior of the bracket, and then brought down in an irregular line toward the center to form the outer border. Within the loops are arranged rosettes w, and in the upper inner corner of the bracket are arranged a series of spindles, y. Between the base R and the upper part, T, is interposed a post, x, in the center of which post is a ring, z.

I ornament the front of the high shelf of the range by a panel, Q, surrounded by parallel embossed ribs or lines d, and between said parallel lines are embossed segments e e. Along the inner side of the inner line are scallops f. Inclosed by these scallops is an embossed monogram on an ornamented background.

The finish or cornice above the top shelf of the range I form of horizontal rails c c and four pedestals, g g g g, between the rails, thereby forming one central and two exterior panels. 55 Within the exterior panels I arrange a series of rosettes, h h, joined or connected together, and within the central panel a series of vertical spindles, i. Over the pedestals I place caps G, and above the central panel a looped band, H, extending along the top rail, between the caps of the inner pedestals.

Upon the top of the caps G and of the looped band H, I place beads a, for the purpose of further embellishing same. 65

Having thus described my invention, what I claim, and desire to secure by Letters Patent, is—

1. In a stove or range, the design for hearth, consisting of rectangular panels and intervening circular panels, all arranged in a row, on said base, a bar or line extended in the form of a rectangular loop across the central portion of each rectangular panel, small raised circles with depression in center along the sides of the said bar or line, and a rosette in each of the circular panels, as shown. 70

2. The design for the exterior of a stove or range, consisting of a panel having a checkered internal field surrounded by a raised molding or border, substantially as shown and described. 80

3. The design for the exterior of stoves and ranges, consisting of a panel having a checkered internal field, a molding surrounding said field, points or triangular projections on the exterior of the molding, and rosettes outside of said points, substantially as shown and described. 85

4. The design, in a cooking stove or range, consisting of the ornamental supporting-brackets of the high shelf, having the reticulated base, and the approximately triangular-shaped upper part, composed of a band formed into square and rectangular loops, with rosettes in the square loops, substantially as shown and described. 90

5. The design for the supporting-brackets of the top shelf of a range, consisting of the reticulated base, and the approximately triangular-shaped upper part, composed of a band formed into square and rectangular loops, rosettes in the square loops, spindles in the corner of the 100

over

bracket, the post interposed between the base and upper part, and the ring on the central portion of said post, substantially as shown and described.

5 6. The design, in a cooking stove or range, consisting of the ornamental panel on the face of the smoke-flue of the high shelf, having the parallel embossed ribs, embossed segments between said ribs, and scallops along the inner side of the inner rib inclosing the monogram upon an ornamental ground, substantially as shown and described.

10 7. The design for the cornice above the high shelf of a range, consisting of the horizontal rails, intermediate supporting pedestals, ro-

settes between the rails of the exterior panels, spindles between the rails of the central panel, caps over the pedestals, the looped band between the central caps, and beads on top of the said caps and band, as shown.

20

In testimony whereof I have hereunto signed my name and affixed my seal, in the presence of two attesting witnesses, at Syracuse, in the county of Onondaga, in the State of New York, this 27th day of July, 1886.

JOHN REIFFENSTEIN. [L.S.]
